Specification for Design.

Patented Mar. 14, 1922.

Application filed January 15, 1921. Serial No. 437,593. Term of patent 3½ years.

To all whom it may concern:

Be it known that I, JAMES P. RICHARDS, a subject of the King of Great Britain, and resident of the city of Toronto, county of York, Province of Ontario, in the Dominion of Canada, have invented a new, original, and ornamental Design for a Package for Rubber Bottle Nipples and Soothers, of which the following is a specification, refer-

ence being had to the accompanying drawing, forming part thereof.

The drawing is a perspective view of the package shown in the open or display position.

I claim:

The ornamental design for a package for rubber bottle nipples and soothers, as shown.

JAMES P. RICHARDS.
